UNITED STATES PATENT OFFICE.

WILLIAM L. NUCKOLS, OF MILLVILLE, MISSOURI.

IMPROVEMENT IN CAR-COUPINGS.

Specification forming part of Letters Patent No. **179,946**, dated July 18, 1876; application filed May 22, 1876.

To all whom it may concern:

Be it known that I, WILLIAM L. NUCKOLS, of Millville, Ray county, and State of Missouri, have invented a new and Improved Car-Coupling, of which the following is a specification:

In the accompanying drawing, Figure 1 is a top view of my improved car-coupling, partly in section, to show the construction. Fig. 2 is a vertical longitudinal section of the same, and Fig. 3 is a side view of one of the dogs.

This coupling is an improvement in the class known as "automatic;" and the feature of novelty is the means for holding the link at various angles, to adapt it to enter the draw-heads of other cars of the same or different height, and engage with a pivoted coupling-pin or other equivalent device, and thus couple two cars together.

The bumper-heads A have long tapering cavities, and a double incline, a' , is formed on or attached to the floor thereof. The L-shaped coupling-pin has trunnions b' , and is held in place by dogs C.

When in the vertical position the pin abuts the end walls of the slots in the top portion and floor of the draw-heads, and is thus enabled to withstand the strain to which it is necessarily subjected by applied traction.

In the rear corner of the coupling-pin B is formed a notch, for convenience in raising it in uncoupling the cars; or a ring may be attached to it, to receive a chain or rod for uncoupling.

E is a spring, the forward end of which is attached to the forward part of the lower side

of the bumper-head A, and which passes up and back through the slot in the lower side of said bumper-head.

F is a lever, pivoted to and between two bars, G, attached to or formed upon the lower side of the bumper-head A. The forward end of the lever F rests against the lower side of the spring E.

In adjusting the coupling to couple the cars automatically as they are run together, a link, D, is inserted in the cavity of the bumper-head A, and pushed back beyond the coupling-pin B. The lever F is then operated to raise the free end of the spring E, and the link is drawn forward beneath it more or less, according as the forward end of the said link is to be held higher or lower to bring it into a position to enter the bumper-head of the adjacent car as they are run together. As the forward end of the link D enters the bumper-head of the adjacent car and strikes, pushes back, and passes the coupling-pin, its rear end is pushed back from the spring E, allowing the said spring to drop down out of the way, and the link is again free from said spring.

Having thus described my invention, what I claim as new, and desire to secure by Letters Patent, is—

The combination of the spring E and lever F with the lower side of the bumper-head A, substantially as herein shown and described.

WILLIAM L. NUCKOLS.
